BUNK BED

Allan Brill, Cicero, Ill.

Application February 18, 1952, Serial No. 18,574

Term of patent 14 years

(Cl. D5—4)

To all whom it may concern:

Be it known that I, Allan Brill, a citizen of the United States, residing at Cicero, in the county of Cook and State of Illinois, have invented a new, original, and ornamental Design for a Bunk Bed, of which the following is a specification, reference being had to the accompanying drawing, forming part thereof.

Fig. 1 is a perspective view of a bunk bed, showing my new design;

Fig. 2 is an enlarged perspective view of the upper portion of a side pillar of the end-piece; and

Fig. 3 is an enlarged section on the line 3—3 of Fig. 1.

The characteristic features of the design reside in the solid line portions.

I claim:

The ornamental design for a bunk bed, as shown and described.

ALLAN BRILL.
